Haworth & Haworth.

UNITED STATES PATENT OFFICE.

THOMAS W. PEDERSEN, OF NEW YORK, N. Y., ASSIGNOR TO OIL JACK, INC., OF NEW YORK, N. Y., A CORPORATION OF NEW YORK.

FLUID-OPERATED JACK.

Application filed December 5, 1924. Serial No. 754,118.

This invention relates to improvements in fluid-actuated jacks, and more particularly to jacks that are self-contained and include means for storing the actuating fluid.

5 The principal object of the invention is to provide a jack of this type which shall be generally more efficient and durable than others and shall be considerably less expensive to manufacture.

10 Another object is to provide a fluid-operated jack with means for positively preventing the forcing of the jack stem from the cylinder.

15 A further object of the invention is to provide a fluid-operated jack which shall be leak-proof and which may be carried in any position without loss of fluid.

20 The invention further resides in certain novel and advantageous details of construction as hereinafter set forth and as illustrated in the attached drawings, in which:

Figure 1 is an elevation of a jack made in accordance with my invention;

Fig. 2 is a plan view of the jack;

25 Fig. 3 is a section on the line 3—3, Fig. 1, and

Fig. 4 is a fragmentary section on the line 4—4, Fig. 2.

With reference to the drawings, my jack comprises an integral body member 1 which may be of cast metal, said body having a main chamber 2 and a cylindrical sub-chamber 3 whose function will be described hereinafter. The chamber 2 has at the bottom 35 a central cylindrical recess or depression 4 for reception of the lower end of a cylinder 5 constituting the main cylinder of the jack in which the stem 6 operates.

40 A valve fitting 7 also occupies a position in the recess 4, said fitting lying within the lower end of the cylinder 5 and having a reduced externally threaded extension 8 extending down into a correspondingly threaded recess 9 at the bottom of the recess 4.

45 With the threaded extension 8 the fitting 7 may be screwed down upon a cup-leather or other suitable packing 10 in the bottom of the recess 4.

50 The fitting 7 is provided with a central passage 11 which opens at the top into a recess 12, the passage 11 at the point where it enters said recess being flared or other-

wise formed to provide a seat for a ball valve 13 which normally closes the said passage 11. A rod 14 extending across the top 55 of the recess 12 prevents dislodgment of the ball 13 from its chamber.

As shown in Fig. 3, the extension 8 of the fitting 7 does not reach the bottom of the recess 9, whereby a space 15 is left below the fitting with which the passage 11 communicates, and a passage 16 establishes communication between the said space 15 and the bottom of the chamber 3. In the present instance, the passage 16 extends beyond the chamber 3 to the outside of the body 1. The outer end of the passage 16 may be closed by a set screw 17 or other suitable preferably detachable element.

The cylinder 3 is recessed at the bottom 70 for the reception of a ball valve 18, the latter finding a seat in the bottom of the recess 19, from which a passage 20 extends to the bottom of the chamber 2 outside of the cylinder 5, as shown in Fig. 3. The valve 18 normally closes that end of the passage which opens into the recess 19.

That portion of the body 1 enclosing the chamber 2 is provided at the top with a threaded opening 21 through which the top 80 of the stem or ram 6 projects, and threaded into this opening 21 is a sleeve 22 having an annular recess 23 in its under side for reception of the upper end of the cylinder 5 whereby when the said sleeve 22 is screwed down into place against the top of the cylinder, the latter is clamped in proper position within the body 1, seated at the bottom in the said recess 4 and held at the top within the annular recess 23 of the sleeve 22.

85 The cylinder 5 is provided at its top with a slot or other suitable opening 24 which establishes communication between the interior of the cylinder and the space 25 exterior of the cylinder which, as hereinafter set forth, constitutes a reservoir for the operating fluid.

90 As shown in Fig. 3, the ram or stem 6 is, over the greater portion of its length, 100 slightly smaller than the inside of the cylinder 5, but has at the bottom a section 26 of increased diameter neatly fitting said cylinder, this section guiding the ram in the

cylinder. The stem 6 is provided at the bottom with a recess 27 threaded at its lower end for reception of a threaded extension 28 on a valve fitting 29. The stem is further 5 provided at the top of the section 26 with a cross channel 30 which extends diametrically through the stem and through the upper end of the recess 27. The channel 30 receives a 10 cross or contact bar 31, whose length is approximately the same as the diameter of the stem-section 26, and which is suitably engaged with the upper end of a valve actuating stem 32 which extends loosely through a central opening 33 in the fitting 29. The 15 stem 32 is adapted to engage with its lower end a ball valve 34 seated in the upper end of the lower enlarged section 35 of the opening 33 and normally retained on its seat by a spring 36 confined in the said section 35 by a 20 stud 37 threaded into the fitting. A second spring 38 is confined in the top of the recess 27 and functions normally to hold the stem 32 and bar 31 in an elevated position, as shown in Fig. 3, in which position the ball 25 34 is seated and closing the opening 33. A cup or other packing 39 is held between the fitting 29 and the bottom of the stem 6.

To prevent leakage of the actuating fluid at the top of the chamber 2, suitable packing material 40 may be inserted in the opening 21 above the sleeve 22 and surrounding the stem 6, and a gland 41 may then be threaded down into said opening to compress and expand said packing. The upper 30 end 42 of the stem 6 is, in the present instance, threaded for reception of a load-engaging head 43.

The chamber 3 is cylindrical in form and constitutes a pump cylinder, and is adapted 40 for reception of a pump piston 44, to the bottom of which is secured by a screw 46 a suitable packing element 45. The piston extends upwardly through a suitable packing box 47 in the top of the chamber 3 and connects at the top with a pump lever 48, see 45 Figures 1, 2 and 3. The pump lever 48 is pivotally secured to a boss 49 on the body 1, by means in the present instance of a screw 50, and is connected with the piston 44 through a link 51 the ends of which are 50 pivotally attached to the respective connected parts.

As shown in Fig. 4, the cylinder 5 is provided with a port 52 at a point immediately 55 above the top of the valve fitting 7, said port opening into the reservoir 25. The port 52 is adapted to be closed by a needle valve 53, which extends through an opening 54 in the body 1, the stem of said valve being threaded 60 into a hollow stud 55, which latter is in turn threaded into the opening 54. The stud 55 is adapted to receive packing material which is confined by a gland 57 threaded into the outer end of the stud, leakage around the 65 valve stem being thus prevented. The outer

projecting end of the said stem is provided with a suitable head 58 by which the valve may be adjusted to close or uncover the port 52.

As will be apparent, the actuating fluid is 70 normally contained in the reservoir 25, and operation of the pump piston 44 by means of the lever 48 will cause this fluid first to be drawn into the bottom of the pump chamber 3 through the passage 20, and thereafter 75 on the down stroke of the pump to be forced through the passage 16 and valve 13 into the bottom of the cylinder 5. In this manner, the stem 6 may be elevated until the ends of the bar 31 strike the under side of the sleeve 80 22, whereupon the valve 34 will be opened by depression of the bar 31, with the result that a by-pass is provided for the fluid from below the stem 6, through the opening 33 of the fitting 29, the channel 30, upwardly 85 around the stem 6, and through the port 24 to the reservoir 25. Continued pumping merely circulates the fluid without affecting the pressure on the stem 6.

During elevation of the stem 6, the needle 90 valve 53 is closed, and when it is desired to return the stem to its normal position, as shown in Fig. 3, the needle valve may be adjusted, as previously described, to uncover the port 52, thereby permitting the fluid to 95 pass from the cylinder 5 back into the reservoir 25.

It will be apparent that my improved jack, by reason of the integral construction of the body, base and pump cylinder, made possible 100 by the use of the removable cylinder 5 and the means for holding the latter in position, is inexpensive to manufacture. The construction is also such as to render assembling the jack easy, thereby further reducing expense of manufacture. It will further be noted that all openings by reason of the improved construction may be effectively packed against leakage, which at the top of the cylinder is further guarded against by 105 provision of the vent 24 through which leakage past the bottom of the stem may be drained back into the reservoir. Provision of the valved by-pass for the fluid, functioning after the stem 6 reaches the top of its 110 travel, also is of marked advantage as preventing undue pressure in the pump with possible breakage of the parts and forcing of the stem from the cylinder.

It is, obvious that the jack as herein described may be considerably modified in detail without departure from the essential features of the invention as defined in the appended claim.

I claim:

A fluid operated jack comprising a casing 125 enclosing a reservoir; a recess in the base of said reservoir; a cylinder fitting into said recess and extending through said reservoir; a stem in said cylinder of a diameter smaller 130

than the internal diameter of the cylinder; an enlarged guide portion on said stem slidably fitting said cylinder; a bushing slidably fitting said stem and screwed into an opening in the reservoir casing for retaining the cylinder; a packing gland screwed into the same opening in the reservoir casing; an aperture in the cylinder connecting the annular space between the stem and cylinder with the reservoir; a pump; and means for controlling the flow of fluid from the reservoir to the pump and from the pump to the cylinder. 10

THOMAS W. PEDERSEN.
